BAG HOLDER

Fred S. Elliott, Lansing, Mich., assignor of
one-half to William B. Phillips, Lansing,
Mich.

Application November 5, 1931. Serial No. 573,167

3 Claims. (Cl. 83—26)

This invention relates to a stationary or portable bag holder of the type adapted to hold fabric or other sacks so that the mouth of said sacks may be held in an open position to receive the desired contents. Stationary in that it may be attached to a stationary object such as the side of a grainery or be a part of a machine from which grain or the like is taken away in bags. Portable in that it may be attached to a movable frame secured to a suitable base that may be brought into use wherever desired.

It is an object of this invention to provide a simple and efficient structure of bag holder that will not readily get out of order and will be adapted to hold bags of various sizes, both in circumference and length and that may be placed on the market at a reasonable cost.

I accomplish this object by providing a bag holding device comprising oppositely disposed semi-circular arms adapted to hold the bag, which arms are resiliently held in position and that may be adjustable vertically on a standard secured to a suitable base.

To these and other ends, the invention consists in novel features of construction and combination of elements hereinafter described and clearly set forth in the claims.

The invention can be constructed in a variety of forms and of these I have selected for illustration and specific description herein the one which I consider to exhibit the many features of the invention in their most convenient and effective forms, the embodiment is illustrated in the accompanying drawings of which:—

35 Fig. 1 is a perspective view of the bag holder.

Fig. 2 is a sectional side elevation taken on line 2—2 of Fig. 4 showing the notches and means of holding the bag holder in place on the standard.

40 Fig. 3 is a sectional end view of one of the semi-circular arms showing the construction taken on line 3—3 of Fig. 4.

Fig. 4 is a top plan view of the bag holding device.

45 Fig. 5 is a rear view of the top part of the standard showing the bracket engaging the resilient portions thereof.

Throughout the description and drawings the same number is used to refer to the same part.

50 Referring to the drawings, the bag holder comprises a base 1 which may be constructed of various forms but which is shown as comprising side members 1A between which extend the boards 1B and secured thereto to form a platform.

55 The brackets 2, being part of 1A, are bent in-

ward toward the center of base 1 and are adjacent to the rear thereof. From the center, brackets 2 are bent upward to form standard 3 and are welded at their upper extended end thus forming an inverted Y. The standard being welded at its upper end and secured at its lower end along each side of base 1 allow a slight bow between the base 1 and the welded section of standard 3 to form an added friction in opening 4 of arm support bracket 5. Along the front side of standard 3 are a series of notches 6 in which protrusion 7 of support bracket 5 comes to rest when bracket 5 is set at the desired height as shown in Fig. 2. Bracket 5 has at each end an opening 8 in which semi-circular bag holding arms 9 are placed and held by pins 10.

Pins 10 also form a fulcrum for arms 9. Arms 9 extend backwards and beyond pins 10 to form levers 11 to which one end of springs 12 are securely anchored, the other ends of springs 12 are anchored to protrusions 13 of support bracket 5, thus through springs 12 and levers 11 bag holding arms 9 are held shaped to form an L as shown by the sectional view in Fig. 3, the upright 14 holds the mouth of the bag open and the horizontal extended part 15 keeps the bag from slipping off of semi-circular arms.

It will be noticed in Fig. 2 that to raise or lower bracket 5 by raising arms 9 slightly as shown by broken lines, will draw protrusion 7 of bracket 5 out of engagement with notches 6 of standard 3 so that bracket 5 will be free to be moved up or down, as soon as arms 9 are released and resume a horizontal position bracket 5 will automatically lock in place.

The horizontal protrusions 15 of the semi-circular arms 9 extend horizontally beyond vertical section 14 and perform a protrusion at each end as indicated by 16 and 17. These protrusions tend to force themselves out under the hem at the top of the bag and form a means for holding the sides of the bag from slipping off said semi-circular arms 9.

In practice I have found that the form of my invention illustrated in the accompanying drawings and referred to in the above description as the preferred embodiment, is the most efficient and practical; yet I wish it understood that various minor changes in details of construction may be resorted to without sacrificing any of the advantages of my invention as set forth; for instance, that both arms need not be movable, on the contrary one may be stationary and one movable dependent on the accessibility and requirement.

While I have shown a portable structure to be moved at the convenience of the operator, the same may be attached to a stationary object or machine where the portable features are not required or thought desirable. The standard need not be notched, it was only thought desirable to notch the same to obviate frictional wear of long usage as when new the bow of the standard will cause sufficient friction to hold the bracket rigid at all times.

Having now described my invention I claim as new and novel:—

1. A bag holding device comprising a base a standard raising vertically therefrom said standard being composed of a plurality of vertical strips secured together at their ends, resiliently held apart from each other at their centers and having notches along the forward surface, oppositely disposed semi-circular arms disposed substantially at each end of a bracket, said bracket provided at its center with a transverse opening through which the standard may pass, said transverse opening being provided with a horizontal protrusion which comes in locking contact with the aforesaid notches thereby holding said bracket at any desired height, said semi-circular arms disposed substantially in a horizontal plane with their concave sides toward each other, said arms being fulcrumed about vertical pivots, means supplied to hold said arms resiliently apart substantially as shown.

2. A bag holding device comprising a base a standard raising vertically therefrom, said standard being composed of a plurality of vertical strips secured together at their ends, resiliently held apart from each other at their centers, oppositely disposed, semi-circular arms disposed substantially at each end of a bracket, said bracket provided at its center with a transverse opening through which the standard may pass, said semi-circular arms disposed substantially in a horizontal plane with their concave sides toward each other, said arms having outward horizontal protrusions along the lower side of said curved surface forming a bag supporting ledge, said arms being fulcrumed about vertical pivots, means supplied to hold said arms resiliently apart substantially as shown.

80

85

90

3. In a bag holder, the combination with the bag engaging arms, of a bracket supporting said arms, said bracket having a vertical passage through it, a standard comprising two strips of metal arranged in propinquity and having resilient portions slightly separated, said standard portions being constructed to engage the passage of the bracket resiliently permitting the bracket to be moved up and down and held in adjusted position.
